UNITED STATES PATENT OFFICE

2,417,391

CAR TRUCK

Robert B. Cottrell, Chicago, Ill., assignor to
American Steel Foundries, Chicago, Ill., a corporation of New Jersey

Application June 9, 1944, Serial No. 539,441

15 Claims. (Cl. 105—208.2)

1

My invention relates to railway car trucks.

The general object of my invention is to provide a novel tying arrangement for maintaining the truck side frames properly spaced and in squared relationship.

In this arrangement, a spring plank extends between the side frames and is received at each end thereof within a pocket formed in the inboard side of the associated frames, each frame being provided with interlocking bosses received within complementary openings in the spring plank. A novel locking member is disposed between the bolster-supporting springs and the extremity of the plank, the transmission of pressure from the compressed springs to the plank maintaining the same in position in the side frame, said member comprising a block forming a portion of the bolster spring seat of the side frame and having an upstanding spring-positioning lug and a depending portion extending through an opening in the seat for engaging the end of the spring plank.

Another object of my invention is the provision of cooperating positioning means on the locking member and side frame, facilitating the entrance and assembly of the locking member with the side frame.

In the drawings:

Figure 1 is a fragmentary side elevation, partly in section, of a railway car truck embodying my invention, only one end thereof being illustrated inasmuch as the truck is symmetrical about its transverse center line, and Figure 2 is a fragmentary sectional view taken in the transverse horizontal plane indicated by the line 2—2 of Figure 1.

Figure 3 is a fragmentary sectional view taken in the transverse vertical plane 3—3 of Figure 2.

Figure 4 is a top plan view of one end of the spring plank.

Figures 5 and 6 show my novel locking block, Figure 5 being a top plan view of the same, and Figure 6 being a side view of the block looking from the right in Figure 5.

The present improvement of tying means for maintaining the truck side frames properly spaced and in squared relationship is illustrated in its embodiment in a railway car truck side frame comprising a compression member 2, a tension member 4, and a column 6 adjacent each end of the frame, defining with said members a bolster opening 8. Beneath the bolster opening the tension member 4 is of box section comprising top and bottom chords 12 and 14 (Figure 3) and inboard and outboard webs 16 and 18, said top

chord being widened and formed with upstanding inboard and outboard flanges 20 and 22 defining a spring seat or shelf 24.

A plurality of springs, diagrammatically shown at 26, 27 and 28, are seated on the seat 24 and are held in position thereon by the cooperative relationship of the upstanding lugs 50 of the seat and lugs 30 of the inboard and outboard flanges 20 and 22 surrounding the respective springs to position the same for cooperation with the downwardly projecting lugs 31 of the bolster 32 in order to support the bolster.

The side frames of the truck are maintained in proper alignment by a spring plank 33 extending 15 therebetween and interconnecting the same to hold the side frames in the proper spacing and to keep them in substantially squared relationship.

In accordance with the present invention, 20 there is provided the novel tying arrangement for securing these desirable results in which the tension member 4 comprises a pocket 34 in the inboard side thereof defined by the top chord 12, a horizontal flange 36 extending therebeneath 25 transversely of the inboard web 16, and by spaced end walls 38, 38 integrally formed with the flange 36 and the top chord 12. The flange 36 is provided with a pair of upstanding bosses 39, 39 received within complementary openings 40, 40 in the spring plank or tie bar 33 which is seated on the flange 36 and projects into the pocket 34. To permit entrance of the spring plank into the pocket 34, the upstanding flanges 42, 42 at opposite sides of the spring plank are relieved as indicated at 43. The end of the spring plank is maintained in position on the bosses 39, 39 of the flange 36 by a locking element or block 44 bearing against the top of the spring plank and holding the same in tight engagement with the flange 36.

The locking member or block 44 is shown in detail in Figures 5 and 6 and said block comprises the T-shaped plate 45 seated on, and fitting within, a complementary recessed portion 48 in the top chord and substantially coplanar therewith. As shown in Figure 2, the plate 46 forms a portion of the seat for the springs 26 and 27 supporting the bolster and has an upstanding lug 50 thereon cooperative with the lugs on the top chord shelf 24 partly surrounding the spring 26 to retain the spring 26 in position therebetween, the faces 52 of the lugs 50 of the block 44 and the top chord 12 being arcuately formed for this purpose and also for cooperating with the lugs 30 of the flanges 20 and 22 for position-

ing the springs 27 and 28. The block 44 also comprises a depending portion or flange 54 extending downwardly therefrom through an opening 56 in the top chord, within the recessed portion 48 thereof, for engaging the upper surface of the spring plank extremity.

It will be apparent that upon positioning the springs 26 and 27 on the portion of the seat 24 defined by the plate 46 of the block 44 underneath the bolster, the pressure exerted by the weight of the bolster and the load carried thereby upon the springs 26 and 27 will be transmitted to the plate 46 of the block 44 to cause the depending flange 54 of the block to bear against the upper surface of the spring plank extremity to securely maintain the spring plank in tight engagement with the flange 54 of the block and in interlocking engagement with the bosses 39, 39 of the flange 36.

It is to be understood that I do not wish to be limited by the exact embodiment of the device shown which is merely by way of illustration and not limitation as various and other forms of the device will, of course, be apparent to those skilled in the art without departing from the spirit of the invention or the scope of the claims.

I claim:

1. In a railway car truck, a side frame comprising top and bottom members and spaced columns defining a bolster opening, said bottom member being of box section beneath said bolster opening with the top chord of said box section widened and formed with upstanding inboard and outboard flanges partially defining a spring seat, upstanding spring-positioning lugs on said seat, springs on said seat, a bolster supported by said springs in said bolster opening, a substantially horizontal flange extending from the inboard side of said bottom member beneath said top chord and defining therewith a pocket, upstanding bosses on said horizontal flange, a spring plank seated on said horizontal flange and comprising openings receiving respective bosses, and a locking member engaging one of said springs and said plank, said member comprising a plate T-shaped in plan view recessed within said top chord and substantially coplanar therewith forming a portion of said spring seat, said plate including a spring-positioning lug on the seat portion thereof and a depending portion extending through said top chord into said pocket for engagement with said spring plank.

2. In a railway car truck, a side frame comprising top and bottom members and spaced columns defining a bolster opening, said bottom member being of box section beneath said bolster opening with the top chord of said box section widened and formed with upstanding inboard and outboard flanges partially defining a spring seat, upstanding spring-positioning lugs on said seat, springs on said seat, a bolster supported by said springs in said bolster opening, a substantially horizontal flange extending from the inboard side of said bottom member beneath said top chord and defining therewith a pocket, upstanding bosses on said horizontal flange, a spring plank seated on said horizontal flange and comprising openings receiving respective bosses, and a locking member engaging one of said springs and said plank, said member including a plate recessed within said top chord and substantially coplanar therewith forming a portion of said spring seat, said plate including a spring-positioning lug on said spring seat portion, and a depending portion extending through said top chord into said pocket for engagement with said spring plank.

3. In a railway car truck, a side frame comprising top and bottom members and spaced columns defining a bolster opening, said bottom member being of box section beneath said bolster opening with the top chord of said box section widened and formed with upstanding inboard and outboard flanges partially defining a spring seat, upstanding spring-positioning lugs on said seat, springs on said seat, a bolster supported by said springs in said bolster opening, a substantially horizontal flange extending from the inboard side of said bottom member beneath said top chord and defining therewith a pocket, upstanding bosses on said horizontal flange, a spring plank seated on said horizontal flange and comprising openings receiving respective bosses, and a locking member engaging one of said springs and said plank, said member including a plate forming a portion of said spring seat and having an upstanding lug thereon cooperatively associated with said first-named lugs for positioning said springs therebetween and a depending portion engaging said plank.

4. In a railway car truck, a side frame comprising top and bottom members and spaced columns defining a bolster opening, said bottom member being of box section with a widened top chord affording a spring seat, spring-positioning lugs on said seat, springs on said seat received between said lugs, a bolster supported by said springs in said bolster opening, a flange projecting from the inboard side of said bottom member beneath said top chord and defining a pocket therewith, a spring plank extending into said pocket, and means securing said plank therewith, said securing means including a plate disposed between one of said springs and said plank, said plate being recessed within said top chord and forming a portion of said spring seat and including an upstanding spring-positioning lug and a depending portion engaging said plank.

5. In a railway car truck, a side frame comprising top and bottom members and spaced columns defining a bolster opening, said bottom member being of box section with a widened top chord affording a spring seat, spring-positioning lugs on said seat, springs on said seat received between said lugs, a bolster supported by said springs in said bolster opening, a flange projecting from the inboard side of said bottom member beneath said top chord and defining a pocket therewith, a spring plank extending into said pocket, means securing said plank therewith, said securing means including a plate recessed within said top chord and substantially coplanar therewith forming a portion of said spring seat, said plate including an upstanding spring-positioning lug on said spring seat portion, and a depending portion extending through said top chord into said pocket for engagement with said spring plank.

6. In a railway car truck, a side frame comprising top and bottom members and spaced columns defining a bolster opening, said bottom member being of box section with a widened top chord affording a spring seat, springs on said seat, a bolster supported by said springs in said bolster opening, a flange projecting from the inboard side of said bottom member beneath said top chord and defining a pocket therewith, a spring plank extending into said pocket, and means securing said plank within said pocket, said securing means including a rigid plate re-

cessed within said top chord substantially coplanar therewith and forming a portion of said spring seat, said plate including a depending portion extending through said top chord into said pocket for engagement with said spring plank.

7. In a railway car truck, a side frame comprising top and bottom members and spaced columns defining therewith a bolster opening, said bottom member being of box section with a widened top chord affording a spring seat, springs on said seat, a bolster supported by said springs on said seat, a flange projecting from the inboard side of said bottom member beneath said top chord and defining a pocket therewith, a spring plank extending into said pocket, and means securing said plank within said pocket, said means including a rigid plate T-shaped in plan view engaging a correspondingly shaped recessed portion of said top chords and substantially coplanar therewith for forming a portion of said seat, said plate including a depending portion extending through said top chord into said pocket for engagement with said spring plank.

8. In a railway car truck, a side frame comprising top and bottom members and spaced columns defining therewith a bolster opening, a spring seat on said bottom member, springs on said seat, means on said seat for positioning said springs thereon, a bolster supported by said springs on said seat, a projection on the inboard side of said bottom member beneath said seat and defining therewith a pocket, a spring plank extending into said pocket, and means securing said plank within said pocket, said means including a locking element seated on a recessed portion of said bottom member and forming therewith said spring seat, said element having means cooperatively associated with said first-named spring-positioning means for positioning said springs and a depending portion extending through said seat into said pocket for engagement with said plank.

9. In a railway car truck, a side frame comprising top and bottom members and spaced columns defining therewith a bolster opening, a spring seat on said bottom member, springs on said seat, a bolster supported by said springs on said seat, a pocket in the inboard side of said bottom member beneath said seat, a spring plank extending into said pocket, means securing said plank within said pocket, said means including a plate seated on said bottom member and forming therewith said spring seat, said plate including an upstanding lug engaging one of said springs for positioning the same, and a depending portion extending through the seat of said bottom member into said pocket for engagement with said plank.

10. In a railway car truck, a side frame comprising top and bottom members and spaced columns defining therewith an opening, a spring seat on said bottom member, springs on said seat, a member supported by said springs on said seat, a pocket in the inboard side of said bottom member below said seat, a tie bar extending into said pocket, a member T-shaped in plan view and recessed within said spring seat and substantially coplanar therewith, said member including 70 spring-positioning means cooperative with spring-positioning means on said seat, and a depending portion extending into said pocket for engagement with said tie bar.

11. A spring seat member comprising a plate 75

T-shaped in plan view forming a spring seat on the top thereof, the cross-piece of said plate having an upstanding spring-positioning lug at the juncture thereof with the leg of said plate, and the leg of said plate having the extremity thereof remote from said lug inwardly turned to provide a transversely extending elongate flange for engaging an associated member.

12. In a railway car truck, a side frame comprising top and bottom members and spaced columns defining a bolster opening, said bottom member being of box section beneath said bolster opening with the top chord of said box section widened and formed with upstanding inboard and outboard flanges partially defining a spring seat, spring-positioning means on said seat, springs on said seat, a bolster supported by said springs in said bolster opening, a substantially horizontal flange extending from the inboard side of said bottom member beneath said top chord and defining therewith a pocket, a spring plank seated on said horizontal flange, and a locking member engaging one of said springs and said plank, said member comprising a plate T-shaped in plan view recessed within said top chord and substantially coplanar therewith forming a portion of said spring seat, said plate including spring-positioning means cooperative with the means on said seat and a depending portion extending through said top chord into said pocket for engagement with said spring plank.

13. In a railway car truck, a side frame comprising top and bottom members and spaced columns defining a bolster opening, said bottom member being of box section beneath said bolster opening with the top chord of said box section widened and formed with upstanding inboard and outboard flanges partially defining a spring seat, springs on said seat, a bolster supported by said springs in said bolster opening, a substantially horizontal flange extending from the inboard side of said bottom member beneath said top chord and defining therewith a pocket, a spring plank seated on said horizontal flange, and a locking member engaging one of said springs and said plank, said member including a plate recessed within said top chord and substantially coplanar therewith forming a portion of said spring seat, said plate including spring-positioning means on said spring seat and a depending portion extending through said top chord and into said pocket for engagement with said spring plank.

14. In a railway car truck, a side frame comprising top and bottom members and spaced columns defining a bolster opening, said bottom member being of box section beneath said bolster opening with the top chord of said box section widened and formed with upstanding inboard and outboard flanges partially defining a spring seat, springs on said seat, a bolster supported by said springs in said bolster opening, a substantially horizontal flange extending from the inboard side of said bottom member beneath said top chord and defining therewith a pocket, a spring plank seated on said horizontal flange, and a locking member engaging one of said springs and said plank, said member including a plate forming a portion of said spring seat and having means positioning its associated spring and a depending portion engaging said plank.

15. In a railway car truck, a side frame comprising top and bottom members and spaced columns defining a bolster opening, a spring seat on

said bottom member, spring-positioning means on said seat, springs on said seat positioned thereon by said means, a bolster supported by said springs in said bolster opening, a pocket in the inboard side of said bottom member beneath said seat, a spring plank extending into said pocket, means securing said plank therewithin, said securing means including a plate recessed within said bottom member and substantially coplanar therewith forming a portion of said spring seat, said plate including a spring-positioning means cooperative with said first-mentioned spring-positioning means, and a depending portion extending through the spring seat of said bottom member into said pocket for engagement with said spring plank.
